[57] CLAIM

The ornamental design for an animated horse figure for
use with child's tricycle, as shown and described.

DESCRIPTION

FIG. 1 is a perspective view of an animated horse figure
for use with child's tricycle showing my new design, it
being understood that the broken lines are for illustra-
tive purposes only and form no part of the claimed
design;

FIG. 2 is a rear perspective view thereof;

FIG. 3 is a side elevational view thereof, the side not
shown being a mirror image of the side shown;

FIG. 4 is a front elevational view thereof;

FIG. 5 is a rear elevational view thereof;

FIG. 6 is a top plan view thereof; and

FIG. 7 is a bottom plan view thereof.

Fig. 1
